UNITED STATES PATENT OFFICE.

JAMES JOSEPH DUFFY, OF MEMPHIS, TENNESSEE.

GATE VALVE.

Application filed October 12, 1926. Serial No. 141,198.

This invention relates to gate valves and it is an object of the invention to provide a device of this kind for use in connection with a laundry tub, washer or the like where rapid emptying is required.

It is also an object of the invention to provide in a device of this kind means to take up wear on the valve proper together with means to assure tight and effective seating of the valve proper without jamming.

The invention consists in the details of construction and in the combination and arrangement of the several parts of my improved gate valve whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawing, wherein:

Figure 1 is a view in top plan illustrating a gate valve constructed in accordance with an embodiment of my invention;

Figure 2 is a sectional view taken substantially on the line 2—2 of Figure 1;

Figure 3 is a sectional view taken substantially on the line 3—3 of Figure 2;

Figure 4 is a view partly in section and partly in elevation of a modified form of invention.

As disclosed in the accompanying drawing, F denotes a frame of requisite dimensions and which has disposed thereover a plate 2 held in applied position by the bolts or nuts 3. The plate 2 is provided with an aperture 4 which is adapted to be positioned directly under an opening in a tank, laundry tub, washer or the like from which rapid emptying is desired.

Opposed members 5 of the frame F are provided therealong with the depending flanges 6, similar ends of which having their lower portions extended to provide bearing arms 7 for an operating shaft 8. One end portion of this shaft 8, as herein disclosed, has fixed thereto a hand lever 9 whereby requisite rocking movement may be imparted to the shaft 8 when desired. The shaft 8 substantially midway of the bearing arms 7 has fixed thereto an upwardly disposed rock-

arm 10, the upper or outer end portion of which is operatively connected, as at 11, to a head 12 carried by the outer end portion of a rod 14.

The rod 14 is slidably disposed through the central portion of a member 15 of the frame F and has its inner portion operatively connected, as at 16, with a valve member 17. The end edge faces of the valve member 17 are provided with the grooves 18 which receive inwardly extended guide flanges or tongues 19 carried by the members 5 of the frame F. The grooves 18 receive these flanges or tongues 19 with sufficient freedom to allow the valve member 17 to move up for close contact with the plate 2 to close the opening 4.

Each end portion of the valve member 17 is provided with a depending flange 20 having its lower edge disposed on a downward incline, said inclined edge being adapted to ride on a correspondingly inclined edge, as at 21, provided on an adjusting bar 22.

Each of the bars 22 at predetermined points therealong is provided with outstanding shanks 23 which are extended through a vertically directed slot 24 of requisite length whereby said bar 22 is supported for adjustment movement in a vertical direction and in substantially a fixed path of travel.

Each of the flanges 6 is provided with the inwardly disposed lugs 25 arranged below a bar 22 and through each of which lugs is threaded from below a screw 26 having contact with the under face of the bar 22. By requisite adjustment of the screws 26 the bar 22 may be properly adjusted with respect to the plate 2 to compensate for wear on the valve member 17 or the coacting face of the plate 2.

When the valve member 17 is moved into closed position upon proper operation of the shaft 8, the coaction between the flanges 20 of the valve member 17 and the inclined edges of the bars 22 will cause the valve member 17 to move toward the plate 2 and thus assure a most effective closing action of the valve member 17. However, to prevent jamming of the valve member 17 I provide the screws 27 each of which is threaded through the outer member 15 of the frame F and in the same plane with the valve member 17. These screws 27 provide adjustable stops with which the valve member 17 contacts when moved into its closed position.

In the embodiment of my invention as ill-

lustrated in Figure 4, the valve member 17' is provided at one end portion with depending flanges 28 between which extends an end portion of a rock arm 29 carried by the shaft 30. The portion of the arm 29 extending between the flanges 28 carries a roller 31. Upon rocking of the shaft 30, by the lever 32 or the like, the requisite sliding movement will be imparted to the valve member 17'.

10 From the foregoing description it is thought to be obvious that a gate valve constructed in accordance with my invention is particularly well adapted for use by reason of the convenience and facility with which 15 it may be assembled and operated, and it will also be obvious that my invention is susceptible of some change and modification without departing from the principles and spirit thereof and for this reason I do not wish to 20 be understood as limiting myself to the precise arrangement and formation of the several parts herein shown in carrying out my invention in practice except as hereinafter claimed:

25 I claim:—

1. A valve structure comprising a plate having a discharge opening, a frame associated with said plate, a slide valve slidably supported by the plate for movement across the opening, said slide valve also having bodily movement toward or from the plate, flanges depending from the slide valve and having their lower edges inclined, bars, said bars having edges inclined similar to the inclined edges of the flanges of the slide valve, and means on the frame for supporting the bars in such position whereby the inclined edges of the flanges of the slide valve engage the inclined edges of the bars when the valve is moved into closed position to force the valve toward the plate, the means for supporting the bars being adjustable to regulate the position of the bars relative to the plate, and means carried by the bars and

co-operating with the frame for guiding the 45 adjusting movement of the bars.

2. A valve structure comprising a plate having a discharge opening, a frame associated with said plate, a slide valve slidably supported by the plate for movement across the opening, said slide valve also having bodily movement toward or from the plate, flanges depending from the slide valve and having their lower edges inclined, bars, said bars having edges inclined similar to the 55 inclined edges of the flanges of the slide valve, means on the frame for supporting the bars in such position whereby the inclined edges of the flanges of the slide valve engage the inclined edges of the bars when 60 the valve is moved into closed position to force the valve toward the plate, the means for supporting the bars being adjustable to regulate the position of the bars relative to the plate, said frame adjacent to the bars being 65 provided with slots, and members carried by the bars and extending within the slots to guide the adjusting movement of the bars:

3. A valve structure comprising a plate 70 having a discharge opening, a frame associated with said plate, a slide valve slidably supported by the plate for movement across the opening, said slide valve also having bodily movement toward or from the plate, 75 flanges depending from the slide valve and having their lower edges inclined, bars, said bars having edges inclined similar to the inclined edges of the flanges of the slide valve, lugs carried by the frame and underlying the 80 bars; and members threaded through the lugs and engaging the bars from below, said members supporting the bars and adjustment of said members regulating the position of the bars relative to the plate. 85

In testimony whereof I hereunto affix my signature:

JAMES J. DUFFY.
